JOSEPH PULLMAN AND ERNEST GROSS, OF BELFAST, MAINE

IRONING APPARATUS

Application filed October 12, 1929. Serial No. 399,277.

This invention is a novel ironing board especially designed for use in pants factories and cleaning and pressing establishments for use in ironing out the seams of trousers legs. 5 The invention provides an ironing board which is expandable and adjustable to suit different sizes and widths of trousers legs, and will hold a trousers leg stretched at full length while being pressed, thereby preventing any wrinkles in the material while ironing same; also an ironing board that can be rotated on its longitudinal axis to bring either side seam of the leg uppermost, so that both inner and outer seams may be properly ironed while the trousers leg is stretched on the board. Other objects and advantages of our invention are hereinafter set forth.

We will explain the invention with reference to the accompanying drawings, which 20 illustrate one practical embodiment thereof, to enable others to adopt and use the same; and summarize in the claims the novel features of construction, and novel combinations of parts, for which protection is de- 25 sired.

In said drawings:

Fig. 1 is a side elevation of our ironing board with the near side bar broken away.

Fig. 2 is a top plan view of Fig. 1 showing the side bars in extended positions.

Fig. 3 is a horizontal section through Fig. 1, showing the side bars partly retracted in full lines, and wholly retracted in dotted lines.

Fig. 4 is a detail view of the supporting tube detached.

Fig. 5 is a detail view of the toggle actuating rod detached.

Fig. 6 is a detail left hand end elevation of Fig. 2.

Fig. 7 is a transverse section on the line 7—7 Fig. 3.

The operative parts of the device may be mounted upon a suitable support 1 adapted 45 to be secured to a table or other suitable base. The support shown has spaced standards 2 and 3 provided with aligned bearings 4 which projects from the base and carries 50 the opposite ironing boards 5 and 6 and the

opposite side bars 11 and 12 and their operating devices. The said tube 4 may be provided with collars 4a, 4b adjacent the legs 2 and 3 to prevent axial movement of the tube, while permitting rotation thereof. 55

The ironing boards 5 and 6 are clamped or otherwise suitably mounted on and secured to the tube 4 at opposite sides thereof. Said boards are preferably alike, and as shown are of relatively narrow width, tapering towards their outer ends, which extend slightly beyond the outer end of the tube 4. Said boards 5 and 6 are preferably of greater width than tube 4, and extend inwardly to a point adjacent the support 1. 60

Within the tube 4 is a non-rotatable but longitudinally movable rod 7, which is slidably mounted in a guide 7a adjacent the inner end of tube 4, and in a guide 7b adjacent the outer end of said tube. Upon rod 7 within the tube are two spaced blocks 8 and 9, said blocks being preferably slidable on the rod 7, but moved by the rod, within the tube, as hereinafter explained. The block 8 is adjacent the inner ends of boards 5 and 6, and block 9 is adjacent the outer ends of said boards. 65

The block 8 is connected to the opposite side bars 11 and 12 by means of links 8a, and the block 9 is connected to the side bars by means 70 of links 9a, said links respectively extending through side openings 4b and 4c in the tube 4. The block 7b is connected to the opposite side bars 11 and 12 by means of links 10a

which extend through openings 4d in the tube 4. The respective links 8a, 9a, 10a are pivoted at their inner ends to the respective blocks, and at their outer ends to the bars 11 and 12, as shown in Figs. 2 and 3. The links 8a, 9a incline in a direction away from the support 1, while the links 10a incline in a direction toward said support 1. Said links 75

taken together form toggle levers which can be made to expand or contract by moving the rod 7 inward or outward. When the toggles are expanded the side bars 11 and 12 are moved away from the tube 4; see Fig. 2. When the toggles are contracted the side bars are moved inwardly toward the tube 4, see Fig. 3. When side bars 11 and 12 are moved 80

fully inward they lie between the boards 5 and 6 on opposite sides of tube 4, as shown.

The links 8a are preferably longer than links 9a and 10a so as to separate the inner ends of the side bars 11 and 12 more than the outer ends thereof to properly expand the usually tapered trouser legs.

When rod 7 is moved outwardly the side bars 11 and 12 will be moved laterally away from the tube 4; and when the rod 7 is moved inwardly the side bars 11 and 12 will be drawn laterally toward the tube.

To permit the side bars 11 and 12 to properly expand to suit various shapes and widths

- 15 of trousers legs, the blocks 8 and 9 are slidable on rod 7 and a coil spring 13 is strung on rod 7 between block 8 and a collar 13a fast to rod 7. An expansion spring 17 is also interposed between block 8 and a collar 17a fast to rod 7.
- 20 When a trousers leg is slipped over the boards and side bars (while the latter are in a retracted position, Fig. 3,) and rod 7 is moved outward so as to distend or separate the side bars 11 the springs 13 and 17 permit the bars 25 to yieldingly separate more or less and stretch the trousers leg properly on the boards, and permit the trousers legs of different widths or different cut to be properly held on the board.

- 30 The rod 7 may be moved inward or outward at the will of the operator by any suitable means. As shown the inner end of rod 7 projects beyond the inner end of tube 4 and is provided with a collar 7e which may be 35 fastened thereon by a nut 7c. The collar 7e is engaged by an operating lever 14, connected to a hand lever 16 pivoted upon the support 1. Lever 16 carries a pawl 16a which engages ratchet teeth 15a on a segment 15 attached 40 to support 1, said pawl 16a being operable by a handpiece 16b on lever 16. If desired the rod 7 could be operated by a foot lever 16b pivoted at 14a on the support 1 and connected to a treadle, (not shown).

- 45 In operation; rod 7 is shifted to move the side bars inward, as in Fig. 3; then a trousers leg, turned wrong side out, is slipped over the boards 5 and 6 and bars 11 and 12. Lever 16 is then shifted to cause rod 7 to move the side bars outward, and springs 13 and 17 permit the side bars to adjust themselves to the size of the trousers leg and fully expand it, the opposite seams in the leg being exposed full length upon the opposite boards 5 50 and 6. After one seam has been ironed the boards and bars may be rotated as a unit on the tube 4 without removing the trousers leg, and the other seam then ironed.

We claim:

- 60 1. An ironing apparatus, comprising a reversible supporting member, a reversible ironing member having a plurality of ironing surfaces on said supporting member, bars at opposite sides of said ironing member, means for moving said bars toward or from

each other, and means for holding them separated to hold a trousers leg slipped over the ironing member in distended position thereon.

2. Ironing apparatus, comprising a reversible supporting tube, a reversible ironing member having a plurality of ironing surfaces on said tube, bars at opposite sides of said tube and member, means for moving said bars toward or from each other, and means for holding the bars in adjusted position to hold a trousers leg slipped over the board in distended position. 70

3. Ironing apparatus, comprising a reversible supporting member, ironing boards 80 disposed at opposite sides of said member, bars at opposite sides of said member and intermediate the said boards, means for moving said bars toward or from each other, and means for holding them separated to hold a trousers leg slipped over the boards in 85 distended position on the boards.

4. Reversible ironing apparatus, comprising a rotatable supporting tube, similar ironing boards disposed at opposite sides of said tube, bars at opposite sides of said tube and in a plane intermediate the said boards, means for moving said bars toward or from each other, and means for holding the boards in adjusted position to hold a trousers leg 90 slipped over the boards in distended position. 95

5. Ironing apparatus for trouser legs and the like; comprising a support, a tube, an ironing board mounted on said tube, leg distending bars at opposite sides of the tube, a rod parallel with the tube, toggle links connecting said bars with said rod and tube with said tube, and means for moving the rod to expand or contract the toggles and thereby 100 cause the bars to separate or approach each other. 105

6. In ironing apparatus for trouser legs and the like; a tube, an ironing board mounted on the said tube, distending bars at opposite sides of the tube and adjacent opposite edges of said board, a rod within the tube, toggle links connecting said rod with the said bars, and connecting the bars and the tube, and means for moving the rod to expand or contract the toggles to move the bars toward or 110 from each other. 115

7. In ironing apparatus of the character specified; a supporting member, an ironing board on said supporting member, a rod extending axially of said supporting member, bars at opposite sides of said member adjacent the edges of said board, blocks slidably mounted on said rod, links pivotally connected with said blocks and with said bars, 120 oppositely disposed links pivotally connected with said bars and with said member, collars on said rods adjacent said blocks, springs engaging said collars and movable blocks, and means for moving the rod to 125 130

cause said springs, blocks and links to yieldingly move the said bars outward.

8. In an ironing board of the character specified, a support, a tube attached to said support; ironing boards disposed at opposite sides of said tube, a rod extending axially through said tube, bars arranged at opposite sides of said tube intermediate said boards, blocks slidably mounted on said rod, links pivotally connected with said blocks and with said bars, oppositely disposed links pivotally connected with said bars and with said tube, said links forming toggle levers, collars on said rods adjacent said blocks, springs interposed between said collars and said movable blocks, means for moving the rod to cause said springs to move the blocks and expand or contract the toggles to move the bars toward or from each other, and means for holding the bars in adjusted position to hold a trousers leg slipped over the board in distended position.
